Specification for Design.

Patented Dec. 20, 1921.

Application filed February 17, 1921. Serial No. 445,894. Term of patent 3½ years.

To all whom it may concern:

Be it known that I, WALTER R. KAHNS, a citizen of the United States, residing at the borough of Brooklyn, county of Kings, city and State of New York, have invented a new, original, and ornamental Design for an Arm-Husk for Lighting-Fixtures, of which the following is a specification, reference being had to the accompanying drawing, forming part thereof, in which—

Figure 1 is a side elevation of an arm husk for lighting fixtures, showing my new design.

Fig. 2 is a rear elevation of the same, and

Fig. 3 is a top plan view.

I claim:

The ornamental design for an arm husk for lighting fixtures, as shown.

WALTER R. KAHNS.
